S. R. Sylvester

UNITED STATES PATENT OFFICE.

SAMUEL R. SYLVESTER, OF WASHINGTON, DISTRICT OF COLUMBIA.

IMPROVED SODA-WATER FOUNTAIN.

Specification forming part of Letters Patent No. 39,331, dated July 21, 1863.

To all whom it may concern:

Be it known that I, SAMUEL R. SYLVESTER, of the city and county of Washington, District of Columbia, have invented a new and useful Improvement in Soda-Water Fountains; and I do hereby declare that the following is a full, clear, and exact description of the same, reference being had to the accompanying drawings, making a part of this specification, in which—

Figure 1 is a side elevation, and Fig. 2 is a vertical transverse section, of my pump, which forms a part of my invention.

Similar letters of reference indicate corresponding parts in the drawings.

This invention relates to that class of soda-water fountains in which the effervescence is produced in the drinking-glass by bringing a solution of supercarbonate of soda or other proper material in violent contact with acidulated sirups, producing soda-water of superior quality at greatly-reduced cost.

To enable those skilled in the art to fully understand and construct my invention, I will proceed to describe it.

A represents a section of a counter or other suitable framing upon which is placed the urn or discharging device B, which is properly secured upon the top thereof A'.

C is a pipe of lead or other suitable material, leading from the urn B to a pump, D, which is secured to the upright portion of the counter A at a a. Another pipe, e, connects the lower portion of the pump with a suitable reservoir, E, placed in any convenient position below the urn or discharging pipe B.

To the pump D, constructed in the ordinary manner, and forming a part of the same, I construct an air-chamber, F, the bottom of which is a movable valve or circular plate, G, working air-tight, or nearly so, and resting on stops g g, and fitted with a hole in its center, through which the piston d of the pump is allowed to work.

H is a cap forming the top of the pump,

with a puckered hole in the center, through which the piston d works air-tight, and which is screwed down to the top portion of the pump or fastened by any other proper means.

I is a coiled or spiral spring surrounding the piston-rod d, its lower end rigidly attached to the valve G and the upper end resting against the cap H. The object of this air-chamber, with its valve and spring, is to produce a uniform velocity of discharge of the solution and continue the same after the piston ceases its upward movement, and which is accomplished by the reaction of the coiled spring pressing downward on the valve.

K is a stop-cock inserted in the discharging-pipe of the urn B at any suitable point, by which the discharge is governed.

To operate my invention the reservoir is filled and the upward stroke of the pump fills the pipes, and the discharge is made with a velocity equal to the pressure given to the piston of the pump.

It is a well-known fact that the beverage ordinarily furnished as soda-water is simply a mineral water and destitute of soda, while by this process, which is cheap and portable, a pure article of soda water is in the reach of all.

Having thus described my invention, what I claim as new, and desire to have secured by Letters Patent, is—

1. The direct discharge of the solution from a single reservoir by means of a spring-pump into the drinking-glass.
2. The pump arranged with a spring or air-chamber, or spring and air-chamber and valve, as and for the purpose set forth.
3. The combination of the single reservoir pipes, spring, pump, and discharging-pipe, substantially as set forth.

S. R. SYLVESTER.
